UNITED STATES PATENT OFFICE

ALFRED L. EUSTICE, OF CHICAGO, ILLINOIS.

FUSE-TERMINAL-ATTACHING MEANS.

1,393,102.

Specification of Letters Patent.

Patented Oct. 11, 1921.

Application filed March 31, 1919. Serial No. 286,446.

To all whom it may concern:

Be it known that I, ALFRED L. EUSTICE, a citizen of the United States, residing at Chicago, in the county of Cook and State 5 of Illinois, have invented certain new and useful Improvements in Fuse-Terminal-Attaching Means, of which the following is a specification.

The present invention relates to a terminal attaching means for renewable fuses; and has for its objects, to provide such a means which will effectively control the discharge of gas incident to blowing of the fuse; which will be convenient to manipulate in assembling and disassembling; free from binding of its parts by fuse metal; and which will be of relatively low cost in production.

The invention proceeds upon the principle of providing an anchoring means which is interlocked against both rotary and longitudinal movement relatively to the terminal, and which is in turn adapted to be confined against both rotation and longitudinal displacement upon the end of the fuse shell, by means of a clamping ferrule or collar.

In my application Serial No. 241,115, filed June 21, 1918, is described a combined gas check and terminal lock end-closure, in which a disk composed of complementary members meeting at the terminal and interlocking therewith against both rotary and longitudinal movement develops an effective gas check at the intersection of the terminal with the disk and affords an anchoring means, which, being clamped over the end of the shell by means of the ferrule and circumferentially interlocked with the shell by means of lugs, affords an effective means for anchoring the terminal against rotation and longitudinal displacement of the shell.

In my application Serial No. 252,334, filed September 3, 1918, is disclosed a combined gas check and terminal lock, according to which a cylindrical disk or flange permanently mounted upon the terminal immediately beneath its shoulders, is fitted within an internal flange upon the end of the shell and locked longitudinally therewith by the shoulders of the terminal on the outside and a pair of projections of the disk on the inside, which latter pass through the flange of the shell with a bayonet joint action, after which a disk is dropped into position to seal the space between the permanent disk

on the terminal and the internal flange on the shell, which disk, being slotted to fit the terminal and carrying projections that drop into end notches of the shell, is adapted to hold all the parts against rotation when the outer ferrule or end cap clamps it to the end of the shell. In such an arrangement, it will be seen that the disk permanently attached to the terminal affords a fixed abutment for securing the terminal against longitudinal movement, also means for centering the disk and its attached fusible link in the shell.

According to the present invention, a permanently attached disk is employed as a centering means and also as a fixed abutment to resist longitudinal movement, but the internal flange on the shell is substituted by a removable member which enters between the fixed abutment and the shoulders of the terminal for anchoring the terminal longitudinally; and this removable member or anchoring disk also takes the place of the locking disk of the former construction, in that, being made to conform to the section of the terminal and carrying lugs that drop into notches in the end of the shell, it also becomes the means for holding the terminal against rotation.

Two embodiments of the present invention are disclosed herein by way of illustration.

Referring to the accompanying drawings; Figures 1 and 2 are axial sectional views in planes at right angles to each other, showing one embodiment of the features of the present invention;

Fig. 3 is a section on the line 3—3 of Figs. 1 and 2;

Figs. 4 and 5 are respectively an under face view of an edge view of the anchoring disk, with its interlocking means in releasing position;

Fig. 6 is a detail view of the terminal with its fixed abutment;

Figs. 7 and 8 are axial sectional views in planes at right angles to each other, showing a modified construction of fuse embodying features of the present invention;

Fig. 9 is a section on line 9—9 of Fig. 7; and

Figs. 10 and 11 are respectively an under face view and an edge view of the anchoring disk, with its unlocking means in releasing position.

In referring to both embodiments of the

invention, 1 represents a shell, which is preferably bushed at its ends by metal liners 2, threaded into the shell at 2^a and having external threads 2^b that receive the securing 5 ferrules 3, as in my previous applications referred to. 4 represents the terminal, which in the present illustrative embodiments is a so-called knife blade terminal; but it is to be understood that as a securing and gas check 10 means, the features of the present invention will be applicable to a terminal which serves only to hold the fusible link within the shell, and to electrically connect the same with the ferrule 3, if it should be desired to use the 15 latter as the means of electrically introducing the fuse into the circuit. Terminal 4 carries a fixed abutment 5, which is preferably in the form of a circular disk which may be made to substantially fit within the bushing 2 and thereby center the terminal and its fusible link within the shell. The fixed abutment is preferably secured permanently to the terminal 4, as, for instance, by striking up the metal, as indicated at 5^x (Figs. 20 1, 6 and 7.)

As thus far described, the construction is not materially different in principle from that of my application Serial No. 241,115, nor different in details of construction from 30 that of my application Serial No. 252,334, and the present construction corresponds even more closely with the latter co-pending application, in that the fixed abutment is preferably provided with an additional lamina of metal 5^a, Figs. 1, 2 and 6, or 5^b, Figs. 35 7 and 8, to better adapt it to serve as a gas check as hereinafter described.

According to the present invention, the 40 means for holding the terminal against longitudinal and rotary motion on the shell comprises an anchoring disk 6, found in both embodiments of the present invention, slotted to fit the section of the terminal 4, and of such diameter that it will fit over the end 45 of the shell and be clamped thereon by the ferrule 3, and which carries lugs or projections 7 that enter notches 8 in the liner of the shell, so that when it is so clamped in position, it will be adapted to hold the terminal 50 against rotation in addition to holding it longitudinally.

The anchoring member 6, according to 55 both embodiments of the present invention, is further provided with means (separately described below), for releasably interlocking it with the terminal 4, which interlocking means preferably also serves to render the anchoring means, in its relation to the terminal and fixed abutment, sufficiently gas-tight to prevent longitudinal discharge of 60 gas incident to blowing of the fuse.

According to the embodiment shown in 65 Figs. 1 to 6, the additional lamina 5^a of the fixed abutment is of less diameter than the disk 5, and the anchoring disk 6 is provided

with an annulus that fits snugly around the lamina 5^a, like a cylinder fits its piston; and said annulus is divided diametrically into two members 9, swiveled at 7 upon the disk 6, and thereby adapted, when the terminal 4 70 is slipped through the slot 6^a of the disk 6, to swing inwardly about the lamina 5^a and enter between the fixed abutment disk 5 and the shoulders 4^a of the terminal, and so interlock the anchoring disk longitudinally with 75 the terminal.

In this position, it will be seen that the fixed abutment disk 5 overlaps the joint between the annulus formed by the members 9 and the lamina 5^a on the inner side, when 80 said joint is overlapped by the clamping joint 6 on the outside, so that an effective gas check is provided, nor can gas escape along the sides of the terminal blade, for the passage is closed there by the tight fit of the 85 fixed abutment disk 5, and preferably also by the lamina 5^a of the fixed abutment.

With this organization of parts, it is simply necessary to secure the anchoring member 6 against rotation upon the shell, 90 which, as stated, is effected by having the projections 7 on the anchoring member enter the notches 8 in the end of the shell. These projections are conveniently provided, as shown, by extending the pintles of the locking members 9 below the plane of said members. They are preferably not only dropped into the notches 8, but are let into the edge of the fixed abutment disk 5 through means of notches 10 (see Fig. 3), whereby they 100 afford additional security against rotation of the blade of the terminal and also localize the escape of gases blowing adjacent to the notches 8, through which the gases gain access to the threads of the ferrule or end cap. 105

According to the form shown in Figs. 7 to 11, the interlocking means carried by the disk 6 is in the form of a divided disk, the members 9^a of which, pivoted upon the pintles 7, as in the first form, are recessed on 110 their meeting edges to conform to the section of the terminal blade 4, and also to provide tongues 9^{ax} that meet within a slot 4^b of the terminal 4. By this means the anchoring member 6 finds its fixed abutment by direct 115 engagement with the terminal, and to that extent is somewhat similar in principle to the construction shown in application Serial No. 241,115, and the outer lamina 5^{ax} of the fixed abutment disk 5 in this instance, in 120 order that it may serve as a gas check, fits snugly around the blade 4 and is pressed against the locking members 9^a by means of a spring 11 introduced between it and the fixed locking disk.

In the present form, as in the form first described, the projections 7 drop into recesses in the end of the shell to hold the anchoring member 6 against rotation, and the member 6, being firmly gripped upon the 130

terminal 4, is adapted to hold the latter against rotation; and when the anchoring member is clamped upon the end of the shell, it is adapted to hold the parts against longitudinal displacement.

In both forms it will be seen that the internal flange of the ferrule 3 overlaps the anchoring member 6 so as to effectively check the escape of gas around the outer edge of the anchoring member, to compel the gas to escape by way of the circuitous passage afforded by the threads.

I claim:

1. In a fuse, a shell, a terminal, an anchoring member, and means for clamping the anchoring member upon the shell; said terminal having longitudinally presented abutments, a cylindrical portion between said abutments, and a non-cylindrical portion; and said anchoring member comprising a portion adapted to embrace the non-cylindrical portion of the terminal to resist rotation of the latter, and members movable into and out of embrace with the cylindrical portion and between said abutments, and thereby resisting longitudinal movement of the terminal.

2. In a fuse, a shell, a terminal, an anchoring member for the terminal, and means for clamping the anchoring member to the shell, said terminal having a fixed abutment member, said anchoring member comprising a portion adapted to embrace the terminal to resist rotation thereof, and a locking means entering between a portion of the terminal and its fixed abutment, and said fixed abutment being adapted to overlie the joint between the anchoring member and its locking means.

3. In a fuse, a shell, a terminal having longitudinally spaced shoulders, an anchoring member, and means for clamping the anchoring member to the shell, said anchoring member being slotted to receive the terminal and conforming thereto, and having means for interlocking it to the terminal longitudinally, comprising a pair of members movable on the anchoring member into and out of engagement with the terminal between its shoulders.

4. In a fuse, a shell, a terminal having a fixed abutment and a shoulder spaced therefrom, an anchoring member fitted to the terminal to resist rotation thereof, and having means for interlocking it longitudinally with the terminal, comprising a pair of members pivoted on the anchoring member and swinging into and out of engagement with the terminal between its fixed abutment and its shoulder.

5. In a fuse, a shell, a terminal having a fixed abutment and a shoulder spaced therefrom, an anchoring member fitted to the terminal to resist rotation thereof, and having means for interlocking it longitudinally

with the terminal, comprising a pair of members pivoted on the anchoring member and swinging into and out of engagement with the terminal between its fixed abutment and its shoulder, said fixed abutment having means overlapping the interlocking means to check the flow of gas past the latter.

6. In a fuse, a shell, a terminal entering the shell, an anchoring means embracing the terminal and longitudinally locked therewith; said terminal carrying a disk within the anchoring means, and said anchoring means having projections which engage both the shell and the disk on the terminal.

7. In a fuse, a shell, a terminal, an anchoring means, and means for clamping the anchoring means to the shell, said anchoring means carrying interlocking members pivoted thereon and movable into and out of engagement with the terminal, the pivots of said interlocking members being extended to provide projections on the anchoring member which engage with the shell.

8. In a fuse, a shell, a terminal having a fixed abutment, an anchoring member, and means for clamping the anchoring member to the shell; said fixed abutment having a cylindrical portion, and said anchoring member having means with which it interlocks with the terminal, surrounding said cylindrical portion of the fixed abutment.

9. In a fuse, a shell, a terminal, an anchoring member, and means for clamping the anchoring member upon the shell, said terminal having a fixed abutment comprising a disk and a cylindrical lamina of less diameter than the disk, and said anchoring means having an annular interlocking means overlying the disk of the fixed abutment and conforming to the circumference of its reduced lamina.

10. In a fuse, a shell, a terminal, an anchoring means for said terminal, and a fixed abutment on the terminal engaged by said anchoring means; the fixed abutment comprising a disk having a cylindrical portion of reduced diameter, and the anchoring means comprising a disk having an annular interlocking means which lies between the disk of the anchoring means and the disk of the fixed abutment and surrounds the reduced portion of the latter.

11. In a fuse, a shell, a terminal extending into the shell, an anchoring means comprising a disk slotted to receive the terminal and having means for interlocking it longitudinally with the terminal, and said terminal having a fixed abutment comprising a disk and a portion adjacent to the disk of less diameter than said disk; the interlocking means of the anchoring member comprising a pair of members pivoted upon the anchoring member, overlying the disk of the

fixed abutment, and swinging into and out of embracing relation to the reduced portion of the fixed abutment.

12. In a fuse, a shell, a terminal entering the shell, an anchoring member for longitudinally and circumferentially fixing the terminal relatively to the shell, comprising an anchoring disk slotted to receive the terminal and provided with a pair of interlocking members pivoted upon its face and having their pivots extended to form inward

projections on the anchoring member, said terminal being provided with a fixed abutment disk radially overlapping the interlocking means of the anchoring member, 15 and the inward projections on the anchoring member being notched into both the fixed abutment disk and the end of the shell.

Signed at Chicago, Illinois, this 26th day of March, 1919.

ALFRED L. EUSTICE.
